SPARK PLUG ELECTRODE

Wilfred A. Bychinsky, Ann Arbor, Mich., assignor
to General Motors Corporation, Detroit, Mich.,
a corporation of Delaware

Application June 7, 1949, Serial No. 97,645

4 Claims. (Cl. 123—169)

1

This invention has to do with improvements in electrodes for use in spark plugs and is particularly concerned with the improvement in the center electrodes of spark plugs used in high compression engines of high output such as those employed in aircraft. One of the problems encountered in such spark plugs is that of providing an adequate cooling rate for the center electrode and the tip of the insulator which surrounds it and in addition providing for a controlled dissipation of the heat generated in this area of the spark plug. Unless adequately cooled, the tip of the insulator is subject to heat stresses with the attendant fractures, thereby destroying its usefulness and requiring replacement. Another difficulty commonly encountered if cooling is inadequate is that the tip of the insulator or the portion of the center electrode exposed in the combustion chamber may be heated to a sufficiently high temperature to cause pre-ignition of the fuel charge with consequent interference with engine operation.

The invention is described and particularly pointed out in the following description.

In the drawing:

Figure 1 is a vertical section of the improved spark plug;

Figure 2 is a sectional view taken on line 2—2 of Figure 1; and,

Figure 3 is a perspective view of the center electrode of the spark plug.

In the drawing, 10 indicates the shell of the spark plug threaded at 12 for mounting in the engine. The shell is illustrated as being formed of two parts 14 and 16 secured together by silver soldering as at 18 and clamping between them the shoulder 20 of the insulator 22. The insulator is illustrated as of a well known type having an integral tubular extension 24 at one end serving as an insulating liner for the upper portion 16 of the shell which also serves as a shield to prevent radiation of electrical energy which would interfere with radio transmission or reception.

Insulator 22 is provided with a central bore 26 having different diameters along its length connected by conical portions 28 and 30 providing seats for portions of the electrode. On seat 28 rests the partially conical head 32 of the core 34 of the lower portion of the electrode. It will be noted from Figures 2 and 3 that the conical head 32 is cut away on opposite sides so that it does not completely close the bore by engagement with the seat 28. At its lower end the core 34 is provided with an annular flange 36 which closely

fits the bore of the insulator at the tip. The portion 38 of the core below the flange 36 may be of the same composition as the remainder of the core or may be made of metal more resistant to corrosion and spark discharge, such as platinum alloy. The remainder of the core may be made of nickel or nickel alloy commonly used in spark plug electrodes. Between the conical seat 28 and the flange 36 the core 34 is of less diameter than the insulator bore and the surrounding space is filled with metal of high heat conductivity, preferably silver cast in place as indicated at 37. This may be accomplished by mounting the core 34 in the bore as shown and placing about it or above it in solid or powdered form a sufficient amount of silver and thereafter heating the insulator to melt the silver and cause it to flow into the position shown. The same thing may likewise be accomplished by pouring molten silver into the bore after the core 34 has been assembled in it or by providing the core, prior to assembly, with a surrounding sleeve of silver and thereafter inserting the assembled core and sleeve into the bore and heating the assembly to melt the silver in place. This latter method will not be as satisfactory as the method first described because the space will not be completely filled with silver.

The remainder of the construction follows conventional practices with 42 indicating a conducting glass seal; 44 a glass bonded resistance material; 46 a second conducting glass seal, and 48 a third conducting glass seal surrounding and gripping the lower threaded or grooved end of the upper electrode 50 having an enlarged head 52 seating on shoulder 39 as shown. The glass seals and resistor 44 are fused or softened in place by application of heat, whereupon the upper electrode 50 is pressed into place. The seal and resistance constructions are described and claimed in the following prior patents of Schuartzwalder and Kirk, Patent No. 2,106,578 granted January 25, 1938, Schuartzwalder and Rulka, Patent No. 2,248,415 granted July 8, 1941 and McDougal, Schuartzwalder and Rulka, Patent No. 2,459,282 granted January 18, 1949.

It will be apparent that the lining of cast silver affords a very good path of conductance of heat away from the tip of the insulator, carrying it into the upper portion of the electrode assembly through the conical head 32, the seals 42, 46 and 48, the resistor 44 and the upper electrode portion 50. Some of the heat is also conducted through the shoulder 20 and the shell 10 into the cylinder head and is thus dissipated.

By this means the tip of the insulator is protected from excessive heat shock which might cause fracture and from attaining sufficiently high temperatures to cause pre-ignition.

What is claimed is:

1. In combination, a spark plug insulator having a central bore therein, an electrode in the bore closing the lower end thereof and having a reduced portion extending upwardly therein, said electrode being provided at a point substantially removed from the lower end of the bore with a radially enlarged portion engaging the inner wall of the bore and centering the electrode therein, said enlarged portion having peripheral surfaces radially spaced from said wall to provide communication between the reduced portion of said electrode and the space in said bore above said enlarged portion and good heat conducting metal substantially filling the space between the reduced portion of the electrode and the bore.

2. In the combination as claimed in claim 1, said insulator having an upper portion of the bore enlarged, providing a seat at the junction with the lower portion of the bore, the upper enlarged portion of said electrode being engaged with the seat at circumferentially spaced points.

3. In a spark plug, a spark plug insulator having a central bore comprising a portion of small diameter adjacent the tip of the insulator which is normally exposed in the combustion chamber, and a portion of enlarged diameter spaced therefrom, an electrode comprising a core of heat resistant metal in the bore having an intermediate portion of less diameter than the bore and enlarged ends, one of said enlarged ends being located at the tip of the insulator and substantially filling the bore, the other enlarged end

engaging the portion of the bore of enlarged diameter for centering the core therein and having a peripheral portion removed from the other enlarged end to provide communication

5 between said bore portion of small diameter and said bore portion of enlarged diameter, and metal of good heat conductivity surrounding the reduced portion of the core and filling the said bore portion of small diameter and providing a path of high heat conductivity for the flow of heat away from the tip of the insulator.

10 4. In a spark plug, the combination of a spark plug insulator having a central bore including an upper enlarged portion connected with a lower portion by a conical seat, an electrode having a partially conical head engaging the seat, said head having oppositely disposed flat surfaces inwardly spaced from said conical seat to provide communication between said upper and lower portions and a shank of less diameter than the bore extending downwardly therefrom, said shank being provided at the lower end of the bore with an enlarged portion filling the bore end with an extension serving as a center electrode, the space between the shank portion of the electrode and the wall of the bore being filled with metal of high heat conductivity.
